UNITED STATES PATENT OFFICE.

JAMES LEONARD MOORE, OF WELLSVILLE, NEW YORK, ASSIGNOR TO THE MOORE STEAM TURBINE CORPORATION, OF WELLSVILLE, NEW YORK, A CORPORATION OF NEW YORK.

TURBINE BLEEDER VALVE.

Application filed May 9, 1923. Serial No. 637,778.

To all whom it may concern:

Be it known that I, JAMES LEONARD MOORE, a citizen of the United States, residing at Wellsville, in the county of Allegany and State of New York, have invented certain new and useful Improvements in Turbine Bleeder Valves, of which the following is a full and clear description thereof.

10 This invention relates to bleeder valves as applied to turbines, and more particularly designed and adapted for use in connection with high pressure condensing steam turbines.

15 The objects of the invention are:—

First, to construct and arrange a steam turbine bleeder valve which will not warp or be distorted out of shape due to the great difference of temperature usually existing 20 between the opposite faces of the valve when the bleeder valve is closed.

Second, to construct and arrange a bleeder valve which will not only be maintained throughout at a uniform temperature when 25 in its closed position, but at the same time said valve will be reduced in weight and materially stiffened by the improved construction.

Third, to construct a bleeder valve for use 30 in connection with high pressure condensing turbines having a small leakage through the valve, so that said valve in its closed position is not absolutely steam-tight, whereby a small volume of steam is capable at all 35 times to pass through the interior of the bleeder valve, and final stages of the turbine to the condenser for the purpose of preventing said final stages from becoming overheated.

40 Fourth, to construct and arrange a steam turbine bleeder valve which is supported in two end bearings having a small clearance with the valve stems supporting said valve and the main body of the valve will have a 45 slightly greater clearance in its seat or bored section of the turbine casing, so that the entire weight of the valve will be taken up or carried by said end bearings and not on the larger section or main body of the 50 valve, thereby greatly reducing the friction between the valve and its seat and hence permitting easy and quick operation of the valve under all conditions of service to which the turbine might be subjected.

55 Fifth, to construct a bleeder valve particu-

larly adapted for use in connection with a steam turbine, which will not stick or rust in the turbine casing while remaining in one position during the summer months when steam is not being bled or used in the 60 heating or other auxiliary systems, and hence avoid a common and troublesome defect in bleeder valves now in common use in which no clearance is provided between the valve and the bored section of the turbine 65 casing.

Sixth, to construct the shape of the bleeder valve and arrange or locate the same in the turbine casing, so that a large and unrestricted area or outlet for the passage of the 70 steam from the first to final stages can be provided for or effected, thereby insuring a minimum drop in steam pressure between said stages and providing a high efficiency 75 of operation during the summer months when no steam is bled from the turbine.

Other objects and advantages of the invention will appear from the detailed disclosure of the construction and arrangement of elements and mode of operation to be 80 presently described.

The invention consists of structural characteristics and relative arrangements of elements which will be hereinafter more fully described and particularly pointed out in the 85 appended claims.

In the two sheets of drawings, in which similar reference characters indicate the same parts in the several figures:

Figure 1 is a transverse vertical section 90 of a portion of a turbine provided with the improved bleeder valve, and taken on the line I—I of Figure 2.

Figure 2 is a fragmentary and longitudinal vertical section, taken on line II—II of 95 Figure 1, and

Figure 3 is a fragmentary sectional view, taken on line II—II of Figure 1 when the valve is open.

In the drawings, 10 is the turbine casing which is provided with a live steam or high pressure inlet 11 and a low pressure outlet 12. Within the turbine casing 10 and interposed between the said live steam or high pressure inlet 11 and the low pressure outlet 12 is 100 provided a diaphragm 13, which separates two stages of expansion of the multi-stage turbine, said chamber 14 in the instance illustrated in the drawing being the first or high pressure stage, while chamber 15 is the 105 110

second or a lower pressure stage. The first stage or high pressure chamber 14 is provided with an opening 141 or bleeder connection, (see Fig. 1), which is adapted 5 to be in communication with the heating system, or other auxiliary device of the plant.

In each of said chambers 14 and 15 are respectively stator members 16 and 17 and 10 rotor members 18 and 19, said rotor members 18 and 19 being fixed to a rotary shaft 20 supported in suitable fluid-tight bearings 21 within the front and rear heads of the casing 10 as is common in this class of engines and forms no part of the present invention.

The casing 10 or cylinder of the turbine at the section corresponding preferably at the upper edge of the diaphragm 13 is so 20 formed and constructed as to provide an opening or passageway 22 which forms a communication between the first or high pressure stage chamber 14 and the second or lower pressure stage 15. The cylinder or 25 casing 10 and the upper edge of the diaphragm 13 are bored transversely to the longitudinal axis of the turbine in such a manner as to form jointly a circular valve seat 23 in which is disposed or arranged 30 the rotatable bleeder valve 24. Said bleeder valve 24 is supported and carried by two stub valve stems or spindles 25 and 26, which stems rest in bearings 27, 27, as shown, on either side of the turbine casing 35 10, and said valve stems 25 and 26 are so proportioned with respect to their bearings 27, and arranged with regard to the body of the bleeder valve 24 that said stems or spindles 25 and 26 carry the full weight of 40 said valve 24 and the clearance of the stems 25 and 26 in their bearings is such that said valve 24 may be easily turned by a governor, not shown, and illustrated for example in U. S. Patent No. 801,322 to Kerr, dated 45 October 10, 1905, which may be attached or linked to a lever or arm 28 on the outer end of the stem 26, as indicated in Figure 1, and common in this class of inventions and needs no further disclosure.

50 The main body of said bleeder valve 24 is formed with two longitudinal sections or walls 29 and 30 which are separated to form an enclosed interior chamber 31 within the valve 24, and said chamber 31 is capable of 55 communicating with the first or high pressure stage chamber 14 through an opening 32, and an outlet or bleeder opening or openings 33, for said interior valve chamber 31 is provided in the wall 29, as clearly shown 60 in Figures 2 and 3, and said walls 29 and 30 are so constructed and arranged with respect to the opening 22 and valve seat 23, so that when the valve 24 is turned into its open position, as shown in Figure 3, the two 65 chambers 14 and 15 on the opposite sides of

the diaphragm 13 are in communication with each other through the passageway or opening 22, thereby permitting the partially expanded steam to pass from the first stage to the succeeding stages of expansion and 70 to the final exhaust opening and thence to the condenser, not shown.

When the valve 24 is adjusted in its closed position, or as shown in Figure 2, a slight leakage of steam from the chamber 75 14 to chamber 15 can take place through the opening 32 into the chamber 31 and interior of valve 24 and through the outlet or bleeder opening 33 to the chamber 15. By this arrangement and construction of valve 80 24 with respect to the walls 29 and 30 and openings or outlets 32 and 33 to chamber 31 in relation to the valve seat 23 and chambers 14 and 15, not only will a small quantity of steam be enabled to pass at all times 85 through the final stages of the turbine to the condenser, when the valve 24 is in its closed position, and thereby prevents these final stages from becoming overheated, as when running dry or without expanded 90 steam as in prior turbines provided with bleeder valves, but at the same time, due to the manner of supporting said bleeder valve 24 by the stub shafts 25 and 26, insures the easy turning and operation of the valve at 95 all times and eliminates all danger of the bleeder valve 24 sticking or rusting to its seat during the summer months when the bleeder valve 24 is open, as shown in Figure 3, and no expanded steam is used in 100 connection with the heating system, or for other auxiliary use or apparatus of the plant.

From the foregoing disclosure, it will be 105 readily seen that when the valve 24 is in its closed position, as shown in Figure 2, the steam in bleeding from chambers 14 to 15 passes through the interior of the valve 24 by opening 32, inner valve chamber 31, and opening 33, and in so doing uniformly heats 110 up the two longitudinal walls or partitions 29 and 30 and their connected circumferential sections, in such a manner as to evenly expand or contract all the sections of the valve, and thereby prevent any distortion 115 or warping of said valve 24, which enables the valve to be easily turned in its seat or adjusted under all conditions and temperatures. Said hollow construction of the valve 24 and longitudinal walls 29 and 30 provides 120 a valve not only of unusual lightness, but at the same time of great stiffness and enables the walls or sections of the valve to be made thin, thereby insuring a quick response to sudden changes of temperatures throughout 125 the entire valve portions.

By reference to Figure 3, it will also be seen by the shape and configuration of the valve 24 and its arrangement with respect to the diaphragm 13 and seat 22 in casing 130

- 10, a large undivided or unrestricted cross-sectional area or aperture forming passage-way or opening 22 can be opened up between the two chambers 14 and 15, thereby effecting a minimum reduction in pressure of the steam in passing from chambers 14 to 15 and hence greatly increase the efficiency of the turbine during the six or seven months when no steam is being bled.
- 10 15 20 25 30 35 40 45 50 55 60 65 70 75 80 85 90 95 100 105 110 115 120 125 130
- 10 From the foregoing description of the construction and arrangement of parts, mode of assembling the same and their operation, it will be seen that all the objects and advantages recited in the statement of invention have been fully, efficiently and cheaply carried out, and while the preferred form has been shown and described, it is to be understood that many changes will suggest themselves without in any way varying the essential features of construction or departing from the spirit of the invention as expressed in the claims.

What I claim is:—

1. A multi-stage expansion steam turbine comprising a casing having a live steam or high pressure inlet and final low pressure outlet, means for effecting a plurality of stages of expansion within said casing and interposed between said inlet and outlet, a diaphragm within the casing separating one stage of expansion from a succeeding stage of expansion and provided with an opening for the passage of the steam from one stage to the adjacent succeeding stage of expansion, an intermediate steam pressure outlet communicating with a stage ahead of the diaphragm and receiving expanded steam and exterior of the casing, a rotary bleeder valve disposed in said opening and provided with ports arranged and adapted to control the passage of the expanded steam through said opening from one stage to a succeeding stage or into the intermediate fluid pressure outlet, said bleeder valve provided with a chamber therein having openings or outlets communicating with the exterior of said valve and arranged and adapted to permit the steam to bleed into and through said chamber and valve when said valve is in its closed position, thereby uniformly heating all sections of said valve and permitting a small volume of expanded steam to constantly pass through the other stages of expansion between said diaphragm and final low pressure outlet.
- 10 15 20 25 30 35 40 45 50 55 60 65 70 75 80 85 90 95 100 105 110 115 120 125 130
2. A multi-stage expansion steam turbine comprising a casing having a high pressure inlet and final low pressure outlet, means for effecting a plurality of stages of expansion within said casing and interposed between said inlet and outlet, a diaphragm within the casing separating one stage of expansion from a succeeding stage of expansion and provided with a bleeder valve seat and an opening for the passage of the steam from one stage to the adjacent succeeding stage of expansion, an intermediate steam pressure outlet communicating with a stage ahead of the diaphragm and receiving expanded steam and exterior of the casing, a bleeder valve disposed within said seat and so provided with ports, arranged and adapted to control the passage of the expanded steam through said opening from one stage to a succeeding stage or into the intermediate fluid pressure outlet, said bleeder valve provided with a chamber therein having openings or outlets communicating with the exterior of said valve and arranged and adapted to permit the steam to bleed into and through said chamber and valve when said valve is in its closed position, thereby uniformly heating all sections of said valve and permitting a small volume of expanded steam to constantly pass through the other stages of expansion between said diaphragm and final low pressure outlet.
- 10 15 20 25 30 35 40 45 50 55 60 65 70 75 80 85 90 95 100 105 110 115 120 125 130
3. A multi-stage expansion steam turbine comprising a casing having a live steam or high pressure inlet and final low pressure outlet, means for effecting a plurality of stages of expansion within said casing and interposed between said inlet and outlet, a diaphragm within the casing separating one stage of expansion from a succeeding stage of expansion and provided with an opening for the passage of the steam from one stage to the adjacent succeeding stage of expansion, a bleeder valve seat in the casing adjacent to said diaphragm, an intermediate steam pressure outlet communicating with a stage ahead of the diaphragm and receiving expanded steam and exterior of the casing, a rotary bleeder valve disposed within said seat and provided with ports arranged and adapted to control the passage of the expanded steam through said opening from one stage to a succeeding stage or into the intermediate fluid pressure outlet, said bleeder valve provided with a chamber therein having openings or outlets communicating with the exterior of said valve and arranged and adapted to permit the steam to bleed into and through said chamber and valve when said valve is in its closed position, thereby uniformly heating all sections of said valve and permitting a small volume of expanded steam to constantly pass through the other stages of expansion between said diaphragm and final low pressure outlet.
- 10 15 20 25 30 35 40 45 50 55 60 65 70 75 80 85 90 95 100 105 110 115 120 125 130
4. A multi-stage expansion steam turbine comprising a casing having a live steam or high pressure inlet and final low pressure outlet, means for effecting a plurality of stages of expansion within said casing and interposed between said inlet and outlet, a diaphragm within the casing separating one stage of expansion from a succeeding stage of expansion and provided with a bleeder valve seat and an opening for the passage of the steam from one stage to the adjacent succeeding stage of expansion, an intermediate steam pressure outlet communicating with a stage ahead of the diaphragm and receiving expanded steam and exterior of the casing, a bleeder valve disposed within said seat and so provided with ports, arranged and adapted to control the passage of the expanded steam through said opening from one stage to a succeeding stage or into the intermediate fluid pressure outlet, said bleeder valve provided with a chamber therein having openings or outlets communicating with the exterior of said valve and arranged and adapted to permit the steam to bleed into and through said chamber and valve when said valve is in its closed position, thereby uniformly heating all sections of said valve and permitting a small volume of expanded steam to constantly pass through the other stages of expansion between said diaphragm and final low pressure outlet.
- 10 15 20 25 30 35 40 45 50 55 60 65 70 75 80 85 90 95 100 105 110 115 120 125 130

- stage of expansion from a succeeding stage of expansion and provided with an unrestricted opening for the passage of the steam from one stage to the adjacent succeeding stage of expansion, an intermediate steam pressure outlet communicating with a stage ahead of the diaphragm and receiving expanded steam and exterior of the casing, a hollow bleeder valve provided with ports arranged and adapted to unobstructedly control the passage of the expanded steam through said opening from one stage to a succeeding stage or into the intermediate fluid pressure outlet, said hollow bleeder valve provided with a chamber therein having an opening communicating with the intermediate opening in the diaphragm for the passage of the steam when said bleeder valve is in its open position, whereby said steam is capable of passing into the interior of said valve and uniformly heat the inner portion or unexposed sections of the valve by said steam passing from one stage to a succeeding stage.
5. A multi-stage expansion steam turbine comprising a casing provided with a bleeder valve seat and having a high pressure inlet and final low pressure outlet, a plurality of expansion chambers within said casing and interposed between said inlet and outlet, an intermediate steam pressure outlet communicating with a stage ahead of the diaphragm and receiving expanded steam and exterior of the casing, a bleeder valve provided with ports arranged and adapted to control the passage of the expanded steam from one

stage to a succeeding stage or into the intermediate fluid pressure outlet, said bleeder valve provided with a chamber therein having openings or outlets communicating with the exterior of said valve and arranged and adapted to permit the steam to bleed into and through said chamber and valve when said valve is in its closed position, thereby uniformly heating all sections of said valve and permitting a small volume of expanded steam to constantly pass through the other stages of expansion between said diaphragm and final low pressure outlet.

6. A multi-stage expansion steam turbine rotary bleeding valve provided with a chamber therein having openings or outlets communicating with the exterior of said valve and arranged and adapted to permit steam to bleed into or through said chamber and valve, thereby enabling said steam to uniformly heat all sections of said valve in the open or closed position of said valve.

7. A multi-stage expansion steam turbine hollow rotary bleeding valve formed with two separated longitudinal walls provided with openings or outlets, communicating with the exterior of said valve and arranged to lighten and at the same time stiffen the valve structure and also permit steam to bleed into or through said hollow valve to thereby enable said steam to uniformly heat all sections of said valve in the open or closed position of said valve.

In testimony whereof I affix my signature.

JAMES LEONARD MOORE.
